UNITED STATES PATENT OFFICE

120,743

DESIGN FOR A PAPER DISPENSER UNIT

William B. Petzold, Pittsfield, Mass., assignor to General Electric Company, a corporation of
New York

Application March 26, 1940, Serial No. 91,252

Term of patent 14 years

To all whom it may concern:

Be it known that I, William B. Petzold, a citizen of the United States, residing at Pittsfield, in the county of Berkshire, State of Massachusetts, have invented a new, original, and ornamental Design for a Paper Dispenser Unit, of which the following is a specification, reference being had to the accompanying drawing, forming a part thereof.

In the accompanying drawing, the figure is a view in perspective of a paper dispenser unit showing my new design. The opposite side of the paper dispenser unit presents the same appearance as the side shown.

I claim:

The ornamental design for a paper dispenser unit, as shown and described.

WILLIAM B. PETZOLD.
